UNITED STATES PATENT OFFICE.

ABRAHAM RUBIN, OF NEW YORK, N. Y., ASSIGNOR TO HENRY HYMAN & CO., INC., OF NEW YORK, N. Y., A CORPORATION OF NEW YORK.

CORD CONNECTER.

Application filed June 24, 1922. Serial No. 570,657.

My present invention relates to means for connecting cord terminals to complete an electric circuit as through a telephone plug or the like, and will be best understood from 5 the following description and the appended drawings, in which Fig. 1 is an exterior view of a telephone plug which I have adopted for purposes of illustration; Fig. 2 is a view similar to Fig. 1, with the outer plate of the 10 plug removed; Fig. 3 is a side elevation of Fig. 2; Fig. 4 is a section on the line 4—4 of Fig. 2, looking from above, but with the right-hand holding member in disengaging position, and Fig. 5 is an enlarged view of 15 the terminal used in the illustrative embodiment.

Like reference characters indicate like parts in the several views.

In the illustrative arrangement, a telephone plug 10 of the usual type and having a double terminal is provided at its upper end with contact cups 11 insulated from each other and each connected to one of the terminals in the plug in the usual manner. 20 The contact member 11 is provided with a central opening in which may extend the lower portion 12 of the terminal of a cord 13, this terminal having a sleeve 14 at its upper end into which the end of the cord 25 is entered and soldered in the usual manner to form a connection. The sleeve 14 preferably is flared out somewhat, as at 15, both to prevent the cutting of the cord over the edge of the sleeve and also for a purpose to 30 be more specifically pointed out hereinafter. The plug 10 with its contact members 11 is held in the usual divided insulating casing 35 16, the two-halves being held together by the usual screw 17. In axial alinement with the 40 opening in the contact member 11 is a terminal opening 18 in the casing 16, this opening being large enough to permit the passage of the cord and terminal, and particularly the extended portion 15 of the sleeve 14. 45 The end 12 of the terminal passes through the opening in the contact member 11.

In the form shown, I provide a holding member which consists of a flat metal spring member 19 bent so that its lower end is 50 fastened under the nut 20 of the plug 10, and bent again at its upper end so as to pass across the axis of the cord 13 when the terminal thereof is engaged with the contact member 11. The holding member 19 is 55 provided with an opening 21 large enough

to permit the passage of the sleeve 14 and is provided at its outer end with a push-button 22 which, preferably, will be made of some insulating material. The holding member 19 is positioned so that normally 60 it stands as shown in Fig. 2, the left member 19 having the center of the opening 21, to the left of the axis of the opening 18 and the center of the contact member 11. In this position, the edge of the opening 21 is adjacent the cord 13 and also extends over the extended portion 15 of the sleeve 14. Preferably, the opening 21 will be extended to merge into a recess 23 of substantially the same diameter as the cord 13, so as to fit 70 around the cord when in the engaging position. By pressing against the button 22, the member 19 is moved to the right (or left) in Fig. 2 until the center of the opening 21 coincides with the axis of the opening 18, 75 whereupon the cord 13 and its terminal 14 can be withdrawn. Unless this occurs, the terminal is held in engagement with the contact member by the pressure of the holding member 19 and by its overlying the end of 80 the sleeve 14.

The arrangement described provides a means by which a cord connector can be connected or disconnected from the contact member readily, and yet is held in engagement with the contact member against considerable longitudinal pull on the cord. 85

In the form illustrated, I have shown a double connector so that a cord may be connected to each of the terminals of the plug 90 10, the arrangement on either side of the center line of the plug being the same.

While I have shown my arrangement in connection with a telephone plug, it will be understood that it may be applied to any 95 arrangement where it is desired to form an electric contact which may be readily disconnected, and yet which is held against displacement until disconnection is desired. It will also be obvious that the embodiment of 100 my invention may be widely varied.

I claim:

1. In a device of the class described, an insulator block having a terminal opening, a contact member in the block and having an 105 opening in axial alinement with said terminal opening, a conductor cord having a sleeve terminal adapted to be entered into the opening in the contact member, and the sleeve extending beyond the periphery of 110

the cord, the terminal being arranged to be passed through said terminal opening and into the opening in the contact member, and a movable flat holding member having an opening in one end large enough to permit the passage of said sleeve, said member being constructed and arranged to be held yieldingly with its opening out of alinement with said terminal opening and to be moved 10 to bring its opening into such alinement.

2. In a device of the class described, an insulator block, a contact member therein having a relatively deep recess, a conductor cord having a sleeve terminal with its upper 15 end extending beyond the periphery of the cord and its lower end provided with a contact portion adapted to extend into and contact with the sides of said deep recess, and a locking member mounted on said block and 20 arranged to be moved at right angles to the cord and into position above said extended portion of the terminal when the terminal is entered in said recess, to lock said terminal

positively against disengagement from the contact member by a pull longitudinally of 25 the cord.

3. In a device of the class described, a conductor cord having a sleeve terminal with its upper end extending beyond the periphery of the cord, a block having an opening 30 arranged to permit the sleeve terminal to be entered into the block only by moving the terminal in a direction longitudinally of the cord, a contact member in the block arranged to engage the terminal when the terminal is 35 entered in the block, and a locking member mounted on said block for movement at right angles to the axis of said opening and held against movement longitudinally of said opening, and arranged to be positioned 40 above the extended portion of the terminal when the terminal is entered in the block, to lock said terminal positively against disengagement from the contact member by a pull longitudinally of the cord.

ABRAHAM RUBIN.
